US0D1113874S

(12) **United States Design Patent** (10) **Patent No.:** **US D1,113,874 S**
(45) **Date of Patent:** **** Feb. 17, 2026**

(54) **DIRECT RADIATING ARRAY ANTENNA**

(71) Applicant: **MacDonald, Dettwiler and Associates Corporation**, Sainte-Anne-de-Bellevue (CA)

(72) Inventors: **Guillaume Deuchst**, Sainte Anne de Bellevue (CA); **Billy Marquez**, Laval (CA); **Stephen Wilson**, Pointe Claire (CA)

(73) Assignee: **MacDonald, Dettwiler and Associates Corporation**, Sainte-Anne-de Bellevue (CA)

(**) Term: **15 Years**

(21) Appl. No.: **29/875,718**

(22) Filed: **May 9, 2023**

(57) **CLAIM**

The ornamental design for a direct radiating array antenna as shown and described.

DESCRIPTION

FIG. 1 is a top perspective view of a direct radiating array antenna.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a rear view thereof; and,

FIG. 8 is a front view thereof.

The broken lines depict portions of the direct radiating array antenna that form no part of the claimed design.

1 Claim, 8 Drawing Sheets
